Primary Examiner—Celia A. Murphy(74) Attorney, Agent, or Firm—TraskBritt, P.C.(57) CLAIM

The ornamental design for a outsole of a shoe, as shown and described.

DESCRIPTION

FIG. 1 is a perspective view of an outsole of a shoe showing my new design; and,

FIG. 2 is a bottom view of an outsole of a shoe shown in FIG. 1.

The uneven broken line immediately adjacent to the shaded area represent the bounds of the claimed design. All other uneven broken lines represent the remaining portion of the shoe. The uneven broken line representations in FIGS. 1-2 are for illustrative purposes only and form no part of the claimed design.
